UNITED STATES PATENT OFFICE.

HARRIOTT GRANT, OF SYRACUSE, NEW YORK.

DESIGN FOR A GARMENT-HOOK.

SPECIFICATION forming part of Design No. 33,019, dated July 31, 1900.

Application filed July 5, 1900. Serial No. 22,642. Term of patent 7 years.

To all whom it may concern:

Be it known that I, HARRIOTT GRANT, of 5 Syracuse, in the county of Onondaga, and in the State of New York, have invented and produced a new and original Design for Garment-Hooks, of which the following is a description.

Figures 1 and 2 are respectively top and inverted plan views of a garment-hook, showing my new design. Figs. 3 and 4 are respectively side and end elevations of said hook.

As shown in the drawings, the leading or material feature of my design consists in a garment-hook which when viewed in top and inverted plan and side elevation presents substantially the appearance of a conventional garment-hook, having the front portions of its side bars crossed, and when viewed in end elevation presents substantially the appearance of an **X**.

A denotes a garment-hook embodying my

design, and a a its opposite side bars, having their front portions crossed at a' between the bottom and top faces a² a³ of the hook.

A garment-hook embodying my design presents a pleasing and characteristic appearance. 25

Having thus fully described my invention, what I claim as new, and desire to secure by Letters Patent, is—

The design for a garment-hook, substantially as herein shown and described.

In testimony whereof I have hereunto signed my name, in the presence of two attesting witnesses, at Syracuse, in the county of 35 Onondaga, in the State of New York, this 26th day of April, 1900.

HARRIOTT GRANT.
